[57] CLAIM

The ornamental design for a triple dresser, as shown and
described.

DESCRIPTION

FIG. 1 is a perspective view of a triple dresser, showing my
new design;

FIG. 2 is an enlarged front elevational view thereof;

FIG. 3 is a right side elevation of FIG. 2, the left side
elevation being a mirror image; and.

FIG. 4 is a top plan view of FIG. 2.

The rear and bottom of the triple dresser form no part of the
claimed design.
